UNITED STATES PATENT OFFICE.

MELVIN L. STONE, OF LEWISTON, MAINE, ASSIGNOR TO DRAPER COMPANY, OF HOPEDALE, MASSACHUSETTS, A CORPORATION OF MAINE.

WEFT-REPLENISHING LOOM.

No. 923,460.

Specification of Letters Patent.

Patented June 1, 1909.

Application filed January 21, 1909. Serial No. 473,456.

To all whom it may concern:

Be it known that I, MELVIN L. STONE, residing at Lewiston, in the county of Androscoggin and State of Maine, have invented 5 certain new and useful Improvements in Weft-Replenishing Looms, of which the following is a specification.

The object of the present invention is to provide means for taking care of the weft- 10 ends of weft-carriers while occupying the magazine of a weft-replenishing loom and until each weft-carrier is transferred into weaving position in the loom.

One embodiment of the present invention 15 is shown in the accompanying drawings, wherein:—

Figure 1, is a side view of the improved mechanism. Fig. 2, is a plan view of a part 20 thereof. Fig. 3, is cross section. Fig. 4, is a detail of one of the weft-carriers.

The drawings illustrate only so much of the loom as is necessary for an understanding of the invention.

The loom has a transerrer A, which acts 25 to transfer a weft-carrier B, from the magazine for spare weft-carriers into weaving position in the loom. This transerrer is like that employed in the now well-known Northrop loom and is shown, for example, in 30 Letters Patent of the United States No. 529,940, November 27, 1894.

The illustrated magazine is one which carries and holds a stack or column of superimposed weft-carriers. As shown it has a guide 35 channel C, for the weft-carrier butts which prevents any substantial endwise movement of the weft-carriers; and it has a guide or support D, for the weft-carrier tips. The active weft-carrier is stopped at the transfer 40 point in co-operative relation with the transerrer A, by stops E, and F.

Each weft-carrier has its own weft-end holder G, which is detachably held thereon. Each holder has a stem H, fitting the hollow 45 of the carrier tip; and also has a recess I, with a notch J, for securing the weft-end. With this construction the weft-end for each carrier is properly held in place while the weft-carrier occupies the magazine, and until 50 it is transferred into weaving position.

The special object of the present invention is to remove these detachable holders G,

from their carriers prior to the transfer of each carrier into weaving position. To this end, there is a cam-track K, alongside the 55 tip-guide D, which engages the holders G. As the carriers advance in the magazine toward the transfer point their holders enter the cam-track, and during their further advance the holders are cammed outwardly 60 until they are wholly freed from their carriers. The guide-channel C, prevents any substantial endwise movement of the carriers during the camming out of the holders. Each holder has the same diameter as the 65 carrier butt; so that after detachment the holders advance equally with the carriers. Each holder is wholly detached from its carrier before the transfer point is reached, so that the carrier is there ready for the transfer; but the holder remains in position holding onto the weft-end until after the transfer, so that the weft pays out during the first 70 flight of the transferred carrier through the shed. The cam-track extends beyond the 75 transfer point, and eventually the detached holders are discharged therefrom into any suitable receiver.

Desirably the weft should be slack between holder and carrier at the time of transfer. 80 To secure this slackness, the cam-track has an inwardly extending path L, which moves the detached holder toward its carrier, thus slackening the weft-end.

To aid in feeding the column of weft-carriers in the magazine, and the outward camming of the holders, a weight M, is employed 85 which forces the weft-carriers along.

I claim:—

1. A weft-replenishing loom having, in 90 combination, a magazine holding a plurality of weft-carriers, each with a detachable weft-end holder; and a cam which engages the holders and removes them as the carriers are fed to the transfer point.

2. A weft-replenishing loom having, in combination, a magazine holding a plurality of weft-carriers, each with a detachable weft-end holder; and a cam-track which engages the holders and removes them as the carriers are fed to the transfer point, and which extends past the transfer point and retains each holder until after its carrier has been 100 transferred into weaving position.

- 2
3. A weft-replenishing loom having, in combination, a magazine holding a plurality of weft-carriers, each with a detachable weft-end holder; and means for removing each holder from its carrier and for moving the detachable holder toward its carrier to slacken the thread.

In witness whereof, I have hereunto signed my name in the presence of two subscribing witnesses.

MELVIN L. STONE.
